IRONING MACHINE FOR JACKETS OF
LITHOGRAPH ROLLERS

Jonas Theodore Lindquist, Skokie, Ill., assignor to
Roberts & Porter, Inc., Chicago, Ill., a corporation of
Illinois

Application July 12, 1952, Serial No. 298,602

6 Claims. (Cl. 38—52)

This invention relates to improvements in ironing machines. The ironing machine embodying the present invention is especially adapted for, but not limited to, ironing the sewed seam portion of relatively thick fabric materials, such as are formed in tubular sleeves utilized as jackets for moistening rollers of lithograph printing machines.

As is well known, dampening rollers for lithograph machines are in the general range of 1½ inches to 5½ inches in diameter, and vary in length from approximately 10½ inches to 88 inches. Such rollers usually include a central core or shaft of metal, surrounded by a body of resilient material, such as rubber, and the latter being covered by one or more layers of suitable resilient fabric material around which an outer jacket or covering of liquid absorbent material is mounted. It is highly desirable to employ an outer jacket or covering of the material which possesses relatively high liquid absorbing characteristics. One of these fabric materials, which has been extensively used, is known as molleton, the thickness of which is usually in excess of ¼ inch and which, in general, has been found highly satisfactory for effecting proper and uniform distribution of liquid over the plate or in transmission to other rollers of the lithograph machine. To save time and for economy, such molleton jackets preferably are pre-formed and are in the nature of tubes. In order to obtain a most satisfactory construction, it is preferred that the rectangular piece of molleton material, in the process of forming as a tube, be sewed with the two free marginal edges disposed in lapped relation to each other, thus forming a seam. The seam portion of the tubular jacket, or sleeve, by necessity is somewhat thicker than the normal thickness of material, and when such a sleeve is mounted on a lithograph roller, would result in a slightly non-circular external contour, and which, under certain conditions, would result in non-uniform distribution of liquid in operating the lithograph machine.

One of the objects of the present invention is to provide a novel ironing machine which is especially adapted for ironing the seam formed incident to sewing together two free marginal edges of relatively thick fabric material.

Another object is to provide a novel ironing machine which is constructed and arranged for pressing the seam portion of pre-formed tubular sleeves of relatively thick fabric material so that said seam portion approximates the normal thickness of the material.

A further object is to provide a novel ironing machine of the character indicated for pressing and compacting material at the seam portion of pre-formed tubular sleeves made of relatively thick fabric material, wherein the seams are formed by stitching together a pair of opposite marginal edges of the material disposed in lapped relation.

Still another object is to provide a novel ironing machine of the character indicated which is especially adapted for ironing seam portions of the entire range of sizes of pre-formed tubular sleeves of relatively thick

2

fabric material, for different size rollers of lithograph printing machines.

Other objects and advantages of this invention will be apparent from the following description, taken in connection with the accompanying drawings, in which:

Figure 1 is a side elevational view of the ironing machine embodying the present invention.

Figure 2 is a front elevational view, part in section, taken substantially as indicated at line 2—2 on Figure 1.

Figure 3 is an enlarged vertical sectional view through the head of the machine taken as indicated at line 3—3 on Figure 2.

Figure 4 is a view similar to Figure 3 showing the head in operating position, in process of ironing a tubular sleeve of fabric material.

Figure 5 is a transverse sectional view of a preformed tubular sleeve of fabric material prior to being ironed.

Figure 6 is a sectional view, taken at line 6—6 on Figure 4, showing a tubular sleeve in process of being ironed.

Figure 7 is a transverse sectional view of a sleeve, turned inside out, in finished, ironed condition.

Referring now to the drawings, the ironing machine, embodying the present invention, is provided with a frame, indicated generally at 10, comprising a pair of spaced-apart upright members 11, at each end, to the upper ends of which members is welded an inverted channel member 12. Each pair of members 11, are rigidly connected, adjacent their lower ends, by angle bar members 14. The lower portions of each pair of upright members are further stabilized and braced by a pair of longitudinally extending members 15.

Mounted on the rear end of the channel member 12 is a pair of upstanding, longitudinally spaced-apart, brackets 17, in which is rigidly mounted the rear end of a horizontally extending arbor 20. As may be seen in Figure 1 of the drawings, the major part of the length of the arbor is free and unsupported, and the forward portion of the arbor is of considerably reduced diameter as compared to the rearward portion, so as to permit telescoping over the forward portion of the arbor tubular sleeves of fabric material of comparatively small diameter, while at the same time the enlarged diametric portion of the rear end of the arbor provides adequate strength and rigidity for the free and unsupported end of the arbor in process of ironing, as will hereinafter be described.

Mounted on the forward portion of the frame is an ironing head, indicated generally at 25, comprising a pair of spaced-apart supporting arms 26, the lower ends of which are pivotally mounted on the outer ends of a shaft 24, journaled in the down-turned flanges of the channel member 12. The upper ends of the arms 25 terminate in horizontally extending portions, which are rigidly interconnected by a shelf member 27, on which is fixedly mounted an electrically driven motor 28, directly connected to a speed reducer 29. Operatively connected to the speed reducer is a driving sprocket 30 which, through the medium of a chain 31, drives a sprocket 32, fixedly mounted on the outer end of a horizontally extending head shaft 33, which is journaled in bearings 34, secured to the underside of the shelf member 27. Fixedly mounted on the shaft 33, substantially at the longitudinal center of the machine, is a pressing or ironing roller 36, the periphery of which (as may be seen in Figure 6 of the drawings) is of arcuate convex contour and, as shown, is preferably knurled.

Adjacent the outer free end of the arbor 20, said arbor is provided with a vertical slot 38, in which is positioned a cooperating pressing or ironing roller 39, journaled on a pin 40, drive fitted in the arbor, as seen in Figure 6 of the drawings. The periphery of the roller 39 is of

arcuate concave contour of approximately the same radius as the peripheral contour of the ironing roller 36.

To effectively carry out the ironing or pressing operation, the fabric being ironed is subjected to the action of steam immediately prior to ironing. For this purpose I provide a tube 43, fixedly secured on the shelf 27 of the head, the forward end of said tube 43 being bent downwardly and reversely so that its open end terminates in close proximity to the periphery of the ironing roller 36, for discharging steam onto the fabric, immediately prior to the fabric passing between the ironing rollers 36 and 39, as seen in Figure 4 of the drawings. The opposite end of the steam supply tube 43 is connected by a section of flexible hose 44, which in turn is connected to a pipe 45, the latter being connected to piping 46 to a convenient source of steam supply. A steam trap 47 is connected into the piping 45—46, in a usual manner as shown. Connected in the upper portion of pipe 45, is a manually operated valve 48 and a mechanically operated valve 49, the latter, when the machine is not operating, is in a closed position, as hereinafter described.

Pivotedly connected at 51 to the horizontally extending portion of one of the side arms 26 of the head is a downwardly extending rod 52, having a turn buckle 53 interposed in said rod. The lower end of said rod is pivotally connected at 54 to a forwardly extending arm 55, the rear end of which is welded to a tubular sleeve 56, mounted on a rod 57, which is rigidly secured in a pair of blocks 58, secured to the forward lower portion of each of the front frame members 11. Welded to the sleeve 56 is a forwardly extending treadle bar 60, the outer end of which is provided with a foot rest 61. Welded to the sleeve 56, substantially centrally of the length thereof (as seen in Figure 2 of the drawings) is a rearwardly extending member 63, on the rearward portion of which is adjustably mounted a counter weight 64. The extreme rear end of the member 63 is guided in its vertical movement by a pair of upright members 65, secured to a cross bar member 66, which in turn is secured to the tie bar members 15 of the frame.

Connected to the arm 55, is an upwardly extending chain 68, the upper end of which is connected to a lever 69, which is pivotally mounted at 70 on a bracket 71, carried by the mechanically operated valve 49. A coil spring 72 is connected to the rear end of the lever 69 and to the pipe 45 for normally maintaining the valve 49 in closed position and for returning the operating lever 69 to inoperative position.

In operating the machine, hand valve 48 is first opened, and when foot pressure is exerted on the foot treadle 60—61, the treadle member 60 is swung downwardly about the axis of the rod 57 and through the medium of the rod 52, the head 25 is swung about the pivot shaft 24, shifting the ironing roller 36 from the position seen in Figure 3 of the drawings, to the position seen in Figure 4 of the drawings, into cooperative relationship with the roller 39 carried by the arbor 20. Prior to such movement of the head through the action of the foot treadle 60—61, the tubular fabric sleeve to be ironed, as indicated at 75, is first telescoped over the free end of the arbor, and as the head moves downwardly incident to actuation of the foot treadle, the sleeve is embraced between the rollers 36 and 39. It is to be understood that normally in performing such an operation, the motor 28 is operating and the ironing roller 36 is caused to rotate so that the knurled outer surface thereof functions as a positive feed, whereby said rollers perform a pressing or ironing operation on the tubular sleeve 75, while at the same time said sleeve is fed longitudinally along the arbor 20. Coincident with the movement of the head 25 into an operating position, by the actuation of the treadle, the arm 55 causes movement of the chain 68 and lever 69 to open the valve 49 for supplying steam to the fabric sleeve at the zone immediately prior to pressure engagement between the cooperating rollers 36 and 39. When the foot

treadle is released, the counterweight 64, carried on the rod 63, returns the foot treadle linkage and the head to inoperative position, as seen in Figure 1 of the drawings, and simultaneously therewith the spring 72 actuates the lever 69 to a position for closing the valve 49.

In order that the machine may be utilized so as to function automatically, once it is placed in operation, a suitable latching device is employed to automatically lock the head 25 in operative position after it has been moved to such position by the action of the foot treadle 61. Pivotally connected at 76, to the arm 55, adjacent the forward end, is an upstanding bar 77 adapted, when withdrawn in a downward direction by the action of the foot treadle 61, to be engaged by a latch member 78, which is rigidly attached to the outer end of a horizontally extending shaft 79, journaled in the depending flanges of the frame member 12. Said latch is formed and positioned to engage the upper end of the bar 77 so as to lock said bar in its downward position of adjustment, and thereby lock the head 25 in its operating position of adjustment, as seen in Figure 4 of the drawings, during which time the mechanically actuated valve 49 is likewise locked in open position for supplying steam in a manner above described. When the fabric sleeve 75 is completely ironed, or in the event that it is desired to interrupt the ironing operation at any time, a hand lever 80, connected to the opposite end of shaft 79, is moved clockwise, with respect to the position seen in Figure 1, until the latch 78 disengages the bar 77, at which time the counterweight 64 causes the head 25 and associated linkage to return to inoperative position, and at which time the steam valve 49 is again closed.

The fabric sleeve 75, as above referred to, is formed as relatively thick material, such as molleton, which is in the general range of $\frac{1}{8}$ inch thick. In pre-forming such sleeves, a rectangular piece of such material is employed and a pair of marginal edges are disposed in lapped relation to each other, as seen in Figure 5 of the drawings, and such lapped portions are stitched, as indicated at 75a, as close as practical to the free edges of the material. By virtue of such stitching to form a tubular sleeve, the extreme edge portions, beyond the stitching, project a short distance beyond the normal outer surface of the formed sleeve, as may be seen in Figure 5 of the drawings, which results in a thickness in the zone of the seam, substantially in excess of the normal thickness of the material. A sleeve thus formed is first placed on the end of the arbor 20 with the seam registering for engagement between the pair of cooperating rollers 36 and 39, and when the ironer is operated in the manner above described, the pressure between the rollers, together with the employment of steam, results in compacting the material in the general zone of the seam, so that the thickness in the seam area is substantially the same as the normal thickness of the material forming the sleeve. After the seam has been ironed between the rollers 36 and 39, as seen in Figure 6 of the drawings, the sleeve is removed from the arbor and turned inside out, as seen in Figure 7 of the drawings, thereby resulting in a pre-formed tubular sleeve of fabric material of substantially uniform thickness throughout. Such a form of sleeve, formed of molleton or other thick fabric, thus eliminates all of the defects above referred to.

It will be apparent that by virtue of the machine above described (after the tubular sleeve is placed on the arbor with the seam area in registration with the rollers 36 and 39, and said rollers engage one end of the seamed area of the sleeve), when said machine is actuated it functions automatically to complete ironing of the full length of the seam area of the sleeve, leaving the hands of the operator entirely free for proper guidance of the sleeve as it is being ironed and fed longitudinally along the arbor.

While I have herein shown and described a preferred embodiment of my invention, manifestly it is capable of

modification and rearrangement of parts without departing from the spirit and scope thereof. I do not, therefore, wish to be understood as limiting this invention to the precise embodiment herein disclosed, except as I may be so limited by the appended claims.

I claim as my invention:

1. A machine for ironing a tubular sleeve of fabric material, comprising a frame, a horizontally extending arbor carried on the frame and having one end free and unsupported, a head pivotally mounted on the frame and having a rotatable ironing member, said head being movable to position said ironing member in cooperating relation to the free end of the arbor for engaging a fabric sleeve when disposed on said arbor, means for driving said rotatable ironing member, whereby when said member engages a sleeve supported on the arbor said sleeve is caused to be fed longitudinally along said arbor, a foot treadle movably mounted on the frame, linkage interconnecting said head and treadle, whereby pressure on the treadle causes movement of the head to position said ironing member in cooperating relation to the arbor, and a counterweight for acting on treadle, linkage and head for returning said head to inoperative position upon release of pressure on said treadle.

2. A machine for ironing a tubular sleeve of fabric material, comprising a frame, a horizontally extending arbor carried on the frame and having one end free and unsupported, a head pivotally mounted on the frame and having a rotatable ironing member, said head being movable to position said ironing member in cooperating relation to the free end of the arbor for engaging a fabric sleeve when disposed on said arbor, means for driving said rotatable ironing member, whereby when said member engages a sleeve supported on the arbor said sleeve is caused to be fed longitudinally along said arbor, a foot treadle movably mounted on the frame, linkage interconnecting said head and treadle, whereby pressure on the treadle causes movement of the head to position said ironing member in cooperating relation to the arbor, and latch means for automatically locking said head in operative position.

3. A machine for ironing a tubular sleeve of fabric comprising a frame, a horizontally extending arbor carried on the frame and having a free end disposed in fixed position relative to said frame, a first rotatable ironing member journaled on the free end of said arbor, a head carried on the frame and having a second rotatable ironing member disposed above the free end of said arbor in normally spaced relation thereto and being downwardly movable toward said free end of the arbor to a position of cooperating peripheral relation with said first rotatable member for engaging a fabric sleeve therebetween when disposed on the arbor, and means operatively associated with said machine to rotate said second ironing member, whereby when said ironing members engage a sleeve therebetween when supported on the arbor said sleeve is caused to be fed longitudinally along said arbor, the sleeve-engaging periphery of said first rotatable member being arcuately concave in cross section, and the sleeve-engaging periphery of said second rotatable ironing member being of convex contour in cross section.

4. A machine for ironing a tubular sleeve of fabric comprising a frame, a horizontally extending arbor carried on the frame and having a free end disposed in fixed position relative to said frame, a first rotatable ironing member journaled on the free end of said arbor, a head carried on the frame and having a second rotatable ironing member disposed above the free end of said arbor in

normally spaced relation thereto and being downwardly movable toward said free end of the arbor to a position of cooperating peripheral relation with said first rotatable member for engaging a fabric sleeve therebetween when disposed on the arbor, and means operatively associated with said machine to rotate said second ironing member, whereby when said ironing members engage a sleeve therebetween when supported on the arbor said sleeve is caused to be fed longitudinally along said arbor, the sleeve-engaging periphery of said first rotatable member being arcuately concave in cross section, and the sleeve-engaging periphery of said second rotatable ironing member being knurled and of convex contour in cross section.

5. A machine for ironing a tubular sleeve of fabric comprising a frame, a horizontally extending arbor carried on the frame and having a free end disposed in fixed position relative to said frame, a first rotatable ironing member journaled on the free end of said arbor, a head carried on the frame and having a second rotatable ironing member disposed above the free end of said arbor in normally spaced relation thereto and being downwardly movable toward said free end of the arbor to a position of cooperating peripheral relation with said first rotatable member for engaging a fabric sleeve therebetween when disposed on the arbor, means operatively associated with said machine to rotate said second ironing member, whereby when said ironing members engage a sleeve therebetween when supported on the arbor said sleeve is caused to be fed longitudinally along said arbor, and steam supply means mounted on said machine and adapted to direct a supply of steam between said rotatable ironing members, said steam supply means positioned so as to direct its entire discharge flow immediately prior to the point between said rotatable members where engagement with a sleeve when disposed on said arbor is effected.

6. A machine for ironing a tubular sleeve of fabric comprising a frame, a horizontally extending arbor carried on the frame and having a free end disposed in fixed position relative to said frame, a first rotatable ironing member journaled on the free end of said arbor, a head carried on the frame and having a second rotatable ironing member disposed above the free end of said arbor in normally spaced relation thereto and being downwardly movable toward said free end of the arbor to a position of cooperating peripheral relation with said first rotatable member for engaging a fabric sleeve therebetween when disposed on the arbor, means operatively associated with said machine to rotate said second ironing member, whereby when said ironing members engage a sleeve therebetween when supported on the arbor said sleeve is caused to be fed longitudinally along said arbor, the sleeve-engaging periphery of said first rotatable member being arcuately concave in cross section, and the sleeve-engaging periphery of said second rotatable ironing member being of convex contour in cross section, and steam supply means mounted on said machine and adapted to direct a supply of steam between said rotatable ironing members, said steam supply means positioned so as to direct its entire discharge flow immediately prior to the point between said rotatable members where engagement with a sleeve when disposed on said arbor is effected.
